UNITED STATES PATENT OFFICE.

JOSEF SEILER, OF LIEGNITZ, GERMANY.

EXPANSIBLE CIRCULAR TABLE.

1,384,925.

Specification of Letters Patent. Patented July 19, 1921.

Application filed March 29, 1920. Serial No. 369,783.

To all whom it may concern:

Be it known that I, JOSEF SEILER, a citizen of the Republic of Germany, residing at Liegnitz, Germany, have invented a new and useful Improvement in Expansible Circular Tables, for which I have filed applications in Germany, dated September 2, 1915, and in Great Britain, dated February 13, 1920, of which the following is a specification.

This invention has reference to improvements in expansible circular tables, and it consists broadly in a round table provided with expansion pieces or plates adapted to fit around its periphery and which normally lie under the table top in approximately the form of a folded fan within a rim which has a screw-thread or like engagement with a member of the frame and can be lowered and raised by rotating it, the arrangement being such that when the rim has been lowered all the plates can be simultaneously swung outward to form the enlarging ring and when the rim is again rotated to raise it the said ring is raised into the plane of the table top. When the rim is again screwed downward the expansion plates are tilted obliquely and return simultaneously into their fan-like position, whereupon they are concealed by again screwing up the rim. The invention also comprises certain novel constructional details herein-after described and specifically pointed out in the appended claims.

An embodiment of the invention is illustrated in the accompanying drawings, in which:—

Figure 1 is a vertical section through the middle of the closed table;

Fig. 2 is a plan view of the table with the stationary top removed to show the arrangement of the expansion plates below same;

Fig. 3 shows in section a portion of the enlarged table top;

Fig. 4 is a plan view of a portion of the expanded table without the central stationary part;

Figs. 5, 6, and 7 show the means for raising the enlarging plates in various positions; and

Figs. 8 and 9 show means for locking the enlarging pieces or plates.

Referring to the drawings, the stationary part of the table consists of the table top *a* which is connected by its downward exten-

sion *g* with a member *d* having four arms arranged in the form of a cross. The rim *b* is adapted to be screwed upward and downward by means of four spiral grooves *w* formed in its inner face, in which grooves the ends *c* of the fixed cross *d* engage. The enlarging plates *r* are hingedly connected at one of their radial edges to carriers *v* by means of hinges *s*, and these carriers can swing and slide up and down on rods *o*. 65

The carriers *v* rest upon a rotatable flat ring *e* provided with pins *g* which extend through slots *u* in the carriers, and the said ring is mounted on rollers *z*, to enable it to be easily rotated, and is guided at its inner edge on rollers *p* mounted on the rods *o*, the arrangement being such that the carriers *v* and the ring *e* move together when the ring is rotated. To prevent the ring being rotated too far, stops *i* against which the carriers *v* abut are provided on the ring *e*; and to limit the upward movement of the free radial sides of the enlarging plates *r*, small plates *n* adapted to engage under the table top *a* are mounted on the inner circular edges of the plates *r*. Under the plates *n*, lie the plate lifters *l*, which are hingedly connected to the carriers *v*, so that they are movable upward, and are provided with an easily moved pendulum-like trip *k*, which 70

slides over a stationary ring *f* that is rigidly connected to the cross *d* and over the ring *e* (see Fig. 6) when the carriers *b* are being swung inward and outward. When the rim *b* with the carriers *v* swung out is screwed 75 upward, the trip *k* leaves the ring *f* and hangs down free. In the downward movement the trip contacts with the ring *f* and tilts the plate lifter *l* upward. Thereby the plates *r* are tilted up, through the plates 80 *n*, so that they automatically take up their fan-like position in being swung inward. During this inward swinging the trip *k* is again turned into its horizontal position.

At the point where the carriers *v* when 100 swung outward lie over the rim *b*, hooks *m* are mounted which normally lie in their inoperative position (Fig. 9). When the rim *b* is raised, projections *y* on these hooks contact with the table top *a*, and thereby the 105 front end of the hooks is depressed and the rear end, which is also formed with a hook, is raised, the latter hook becoming engaged in a seat in the table top *a* and the former being engaged under a plate *h* mounted on 110

the rim *b* and projecting outward a little beyond its periphery, the said rim and the table top *a* being thus coupled together.

The swinging of the plates *r* outward and inward is facilitated by the provision of a hand-grip *t* which is mounted slidably in one of the carriers *v*, while a folding handle *w* enables the rim *b* to be readily rotated.

The expanding or enlarging of the table is effected as follows:—The handle *w* is turned outward and by means of it the rim is rotated to the left until it is arrested by the stops *i*. Then by pulling out one of the carriers *v* (by means of the grip *t* in the case of a large table) the enlarging plates *r* are swung outward. These plates at once take up a horizontal position, the plate lifters *l* not being disturbed in the swinging outward, and form a closed, horizontal stationary ring. By now rotating the rim *b* to the right, with the help of the handle *w* the said ring is raised into the plane of the stationary table top *a*, and at the same time the said rim and table top are drawn together and locked to each other by means of the hooks *m*. The enlarging ring and the table top *a* now form a single flat surface, and the plates *n* being engaged under the table top *a*, the plates *r* constituting the said ring can not become tilted.

In order to restore the expansion members to their position under the table top *a*, the rim *b* is again rotated to the left, thus disengaging the hooks *m* from the plates *h* and the table top. On further rotation of the rim to the left the plate lifters *l* are tilted up when the trips *k* contact with the fixed ring *f* and the several plates *r* are thus, through the plates *n*, tilted so that they take up automatically their fan-like position in swinging inward. Finally, the rim *b* is rotated to the right to raise it into contact with the table top *a* and the handle *w* is folded inward.

What I claim is:

1. In an expandable circular table, the combination of a central support or pedestal, a stationary circular table top supported thereon, rigid arms extending from said support in the form of a cross, a rotatable rim having spiral grooves formed in its inner periphery in which grooves the ends of the said arms are slidably engaged, a plurality of enlarging plates which are normally retained within the rim under the stationary table top and are adapted to be moved outward to form an annulus around the periphery of the said stationary table top, a car-

rier-arm for each enlarging plate, a rotatable ring on which all the said carrier-arms bear and to which each of the said arms is coupled, and means for automatically tilting the said enlarging plates, when they are being moved inward, to cause them to take up automatically under the stationary table top positions in which they overlap each other 65 like the leaves of a folded fan.

2. In an expandable circular table, the combination with a central supporting frame, a stationary circular table top supported thereon, a rotatable rim having a spiral-groove-and-tongue connection with the said frame to adapt it to be raised and lowered thereon, and a plurality of enlarging plates which are normally retained within the rim under the stationary table top and are adapted to be 70 moved outward to form an annulus around the periphery of the said table top, of a carrier-arm for each enlarging plate hingedly connected to the said plate at one of its radial edges and pivotally and slidably carried at its inner end on a vertical pin mounted on the central supporting frame, a rotatable ring on which all the said carrier-arms bear, a pin-and-slot connection between the said ring and each carrier-arm, and a trip 75 device for automatically tilting each enlarging plate as it is being swung inward, substantially as set forth.

3. In an expandable circular table, the combination of a central support or pedestal, a 90 stationary circular table top supported thereon, a rotatable rim having a spiral-groove-and-tongue connection, with the said central support to adapt it to be raised and lowered thereon, a plurality of enlarging plates 95 which are normally retained within the rim under the stationary table top and are adapted to form an annulus around the periphery of the said table top, arms pivotally carried on the central support and hingedly connected to the said enlarging plates, a rotatable ring on which all the said arms bear and to which each arm is coupled by a pin-and-slot connection, hook devices mounted on the said arms and adapted to be operated by the rim 100 contacting therewith when it is rotated to raise it after the said arms have been swung outward, and trip devices for automatically 105 tilting the enlarging plates as they are being swung inward, all substantially as set forth. 110
